ATTORNEY

UNITED STATES PATENT OFFICE.

JOSEPH BURGER, OF BROOKLYN, NEW YORK.

WOOD-HEEL MANUFACTURE.

Application filed January 7, 1928. Serial No. 245,085.

This invention relates particularly to the formation of the heel seats in the tops of the heel blocks.

At the present time these heel seats are usually formed in either of two ways, the first method involving a "barrel" cutter to which the blocks are fed in a special holder, and the second method involving the use of a rotary rasp or toothed disc which cuts out the seat as the block is rotated over the same. The first method is practical where a considerable number of the same size and style heels are to be seated, as the holder must be specially made or set up for each size and style of heel and it only pays to do this when a great number of the same size and style heels can be made up at one time. The second method is used where a lesser number of heels is to be operated on, but this method has the objection that after a first cut is made to remove the rim portion of the heel seat, the machine must be readjusted and a second cut made to remove the central portion of the seat.

Special objects of the present invention are to provide a machine suited to the latter class of work; that is, to the cutting of heel seats in dozen lots, more or less, and which will be capable of finishing the heel seat complete in one and the same operation.

The various novel features of construction, combination and relation of parts by which the foregoing and other desirable objects are attained, will be apparent from the following specification.

The drawing accompanying and forming part of this specification illustrates one practical commercial embodiment of the invention, but as this is primarily for purposes of disclosure, it will be understood that the structure may be modified without departure from the true spirit and broad scope of the invention as hereinafter defined and claimed.

Figure 1 is a broken front elevation of the machine.

Figure 2 is a broken side view of the machine.

Figure 3 is a broken part sectional and diagrammatic view, illustrating the cooperative action of the two cutters which serve to

complete the heel seat in one single operation.

Figure 4 is a similar view illustrating the way in which the present single cutter machine leaves an intermediate ridge which must be removed by a second cut after resetting the machine.

In the machine illustrated, two cutters are provided, one designated 5 for removing the material at 6, Figures 2 and 3, about the edge portion of the heel seat and the other designated 7 for removing the material at 8 about the central portion of the heel seat. This central portion of the heel seat which is not removed by the first cutter is left in the form of a central ridge, as indicated at 9 in Figure 4.

To secure the cooperative effect of the two cutters, the heel block 10 is guided over them after the manner indicated in Figure 2, so that the smaller second cutter will operate on the central ridge portion 9 at the same time that the larger cutter 5 is taking away the surrounding outer portion of the seat. This result is accomplished by bringing the heel seat face of the block against a face plate 11 overlying the cutters and having an opening 12 through which the rims of the cutters project and by the provision of a gage wheel 13 above the cutters against which the rim of the heel block is held while the block is turned to bring all portions of the heel seat into the range of the cutters.

The gage wheel is indicated as vertically adjustable by means of a screw stem 14 and the face plate is indicated as laterally adjustable by means of a carrier plate 15 which can be secured in laterally shifted adjustment by bolts 16.

The edge cutter 5 is shown as carried by a spindle 17, mounted in fixed bearings 18 and operated by pulley and belt drive 19.

The smaller, center cutter 7 is shown as carried by a shaft 20 journaled in bearings 21 carried by a small motor 22 and as driven through bevel gearing 23 from the shaft of this motor. To regulate the depth and relative position of the cut made by this cutter, the motor is shown as pivotally mounted at its upper end on a bolt 24, as secured in its

position of oscillatable adjustment by a securing bolt 25 operating through an arcuate slot 26 in the base of the motor and the supplemental base 27 on which the motor is mounted is indicated as held in different positions of adjustment inclined to the vertical by bolts 28 extending through slots 29 into the supporting base or column 30.

In operation, the heel is usually started as

- 10 indicated in Figure 1, with one corner at the breast end of the block engaged with the gage wheel and then rotated while thus engaged with the wheel clear around to the other breast corner. This extends the cuts 15 of the two cutters all the way about the heel seat, the edge cutter removing the marginal portion of the heel seat and the center cutter removing the central ridge portion which otherwise would be left by the first cutter.
- 20 It will be seen that by a combination of one or more, or all of the adjustments described, the two cutters may be used to simultaneously and cooperatively remove the material to form the complete heel seat in one simple 25 operation. The setting of the gage wheel determines the approach of the edge of the heel block to the larger edge cutter and also what might be termed the "centering" of the heel block over the central cutter.
- 30 In practise, the longitudinal center line of the heel block should be slightly off the center line of the cutter 7, as indicated in Figure 2. The lateral adjustment of the face plate 11 determines the depth of cut 35 made by the edge cutter and also to an extent, the depth of cut made by the center cutter. The latter, however, is susceptible of independent setting, both by the swinging adjustment of the motor frame and by the 40 inclined up and down bodily adjustment of the motor, which serve to regulate the depth of cut and also the position of such cut relative to the center line of the heel. The cutters may be in the form of rotary rasps such 45 as indicated, and while shown as one larger than the other, it should be understood that they may be of the same size, or if found desirable, the same may be reversed as to relative sizes. Other changes may be made to 50 satisfy different requirements or conditions, all within the scope of the following claims. The adjustments disclosed enable the quick setting of the machine to practically any different styles or sizes of heels and only this 55 one setting is required as the entire heel seat is formed in the one single operation.

What is claimed is:

- 60 1. A machine for forming heel seats in wood heels comprising cutters positioned one to trim away the edge portion of the heel seat and the other to simultaneously trim away the central portion of the same heel seat and means for guiding the heel seat face of a wood heel block into properly 65 cooperating relation with said cutters.

2. A machine for forming heel seats in wood heels comprising cutters positioned one to trim away the edge portion of the heel seat and the other to simultaneously trim away the central portion of the same 70 heel seat and means for guiding the heel seat face of a wood heel block into properly cooperating relation with said cutters, said guiding means and the cutters being relatively adjustable to effect different positioning and depth of cuts made by the 75 cutters.

3. In a machine of the character disclosed, a face plate forming a support for a wood heel block, a gage overstanding said face 80 plate to position the rim of a block bearing against the face plate and relatively offset rotary cutters projecting through said face plate into position to operate on different portions of a heel block presented to the face 85 plate and gage means.

4. In a machine of the character disclosed, rotary cutters operating on different centers, means whereby said cutters may be relatively shifted to operate on different portions of a heel block presented thereto and 90 gaging means for properly presenting a heel block to said cutters.

5. In a machine of the character disclosed, rotary cutters arranged in side by side relation and operating on offset centers, means 95 for enabling adjustment of the relatively offset relation of the cutters and means for guiding the heel seat face of a wood heel block 100 in cooperative relation thereto.

6. In a wood heel seat forming machine, a rotary cutter, a second rotary cutter, a motor for driving and supporting said second cutter, means for mounting said motor in variously adjusted relations to enable the desired setting of said second cutter to the first cutter and means for guiding the heel seat face of a wood heel block in proper 105 cooperative relation to said cutters.

7. In a machine of the character disclosed, 110 a cutter, a second cutter operating adjacent the first cutter, mounting means for said second cutter having a swinging and an inclined adjustment and means for guiding the heel seat face of a wood heel in cooperative 115 relation to the cutters.

8. In a wood heel seat forming machine, means for supporting and directing the heel seat face of a wood heel block in a definite 120 rotary movement and cutter mechanism positioned for cooperation with the heel seat face of the heel block to simultaneously remove both the central and the side portions of the heel seat during such rotary gaging movement of the heel.

9. A machine for forming heel seats, comprising rotary cutters of different diameters to cut different arcs and mounted in adjoining relation with their centers offset to simultaneously cut the rim and central por- 130

tions of a heel seat in a heel block presented to the same.

10. A machine for forming heel seats, comprising rotary cutters of different diameters to cut different arcs and mounted in adjoining relation with their centers offset to simultaneously cut the rim and central portions of a heel seat in a heel

block presented to the same and means for enabling relative adjustment of said cutters to predetermine the portions of the heel seat removed by each and the conjoint action of the two.

In testimony whereof I affix my signature.

JOSEPH BURGER.
